UNITED STATES PATENT OFFICE.

OSCAR G. PENDLETON, OF DECATUR, ILLINOIS, ASSIGNOR OF ONE-THIRD TO RALPH RAYMOND THIMENS AND ONE-THIRD TO WILLIAM LARNERS, BOTH OF DECATUR, ILLINOIS.

AIR-BRAKE VALVE.

Application filed October 11, 1921. Serial No. 507,673.

To all whom it may concern:

Be it known that I, OSCAR G. PENDLETON, a citizen of the United States, residing at Decatur, in the county of Macon and State 5 of Illinois, have invented new and useful Improvements in Air-Brake Valves, of which the following is a specification.

This invention relates to valves and comprehends a construction adapted for use 10 in air brake systems.

It is a well known fact that in air brake systems, draw bars are frequently separated from their connections incident to the application and release of the brakes, especially on long trains, where it is impossible to take care of the slack, due to the relative difference in the efficiency of the braking system at various points throughout the 15 length of the train. Again, in braking systems now in use, it is necessary to apply all the brakes at the same time, and when the latter are used in descending mountains or steep grades, they cause an over heating of the wheels, which often times necessitates 20 stopping the train, with a resultant loss of time to allow the wheels to cool.

It is therefore the chief characteristic of the present invention to provide a valve located in the train line, and designed to 30 permit the brakes to be alternately applied and released at opposite ends of the train in a manner to prevent undue strain upon the draw bars, as well as to eliminate heating of the wheels under any and all 35 conditions, thus removing the objections hereinabove noted in the air brake systems now in use.

The nature and advantages of the invention will be better understood when the following detailed description is read in connection with the accompanying drawing, the invention residing in the construction, combination, and arrangement of parts as 40 claimed.

In the drawing forming part of this application, like numerals of reference indicate similar parts in the several views and wherein:

Figure 1 is an elevation of the valve showing it coupled with the sections of the train line.

Figure 2 is a vertical sectional view through the valve.

Figure 3 is a sectional view taken on line 2—2 of Figure 2.

Figure 4 is a fragmentary sectional view of a modified construction.

The valve forming the subject matter of the present invention comprises a valve casing indicated at 10 and provided with nipples 11 which project from the casing at directly opposite points adjacent the lower end thereof. These nipples have suitably coupled therewith, the sections 12 and 13 of the train line as illustrated in Figure 1.

The casing 10 is closed at its lower end by a removable bottom 14 which may be secured to the casing 10 in any suitable manner. The casing is preferably formed with a flange 15 for this purpose, while the bottom 14 is equipped with a similar flange 16, and through which flanges suitable fastening elements 17 are passed as illustrated in Figure 2. The air line pressure is admitted to and exhausted from the casing 10 through the nipples 11, and this communication between the air line sections 12 and 13 respectively and the valve casing 10 is controlled by means of the valve to be presently described. This valve has a configuration similar to a spool and includes upper and lower pistons 18 and 19 respectively which are connected by a central body portion 20 which is reduced to provide a space 21 between the body portion 20 and the 50 casing 10, although the pistons 18 and 19 fit snugly against the wall of the casing as illustrated. The body 20 of the valve is formed with a bore 22 which is open at one end and closed at the other, a spring 23 being positioned in said bore and operated to normally hold the valve in the position shown in Figure 2. For this purpose, one end of a spring bears against the closed end of the bore, the other end bearing against 55 the top of the casing 10. The casing 10 is provided with a passage 24 arranged immediately beneath and communicating with one of the nipples 11, and also communicates with a passage 25 formed in the removable bottom 14, and which passage 25 terminates to communicate with the casing 10 as at 26.

However, the communication between the passage 24 and the passage 25 is controlled by a spring pressed valve 27, the stem of which slides in a hollow exten- 60 65 70 75 80 85 90 95 100 105

sion 28 formed on a nut 29 which is threaded in a hollow boss 30, the latter depending from the bottom 14. The bottom 14 is also provided with a port 31 for a purpose to be hereinafter described. The casing 10 is formed with arcuate-shaped passages 32 and 33 respectively which lead from the nipples 11, the adjacent ends of these passages opening as at 34 into a reducing valve indicated generally at A in Figure 1. This valve A may be of any wellknown construction, and is of course employed to maintain a reduction in pressure in the air line at the left hand side of the valve casing 10, as compared to the normal pressure of the system at the engine side of the valve.

It is of course understood that the valve forming the subject matter of the invention is used to the best advantage with a long train of cars, and that the valve can be positioned at any point in the train line system found most desirable. In practice, when the valve is initially arranged in the train line, the valve proper assumes the position illustrated in Figure 2, in which position the nipples 11 are in open communication with each other. When air is subsequently admitted to the train line, it passes through the valve casing from the section 12 of the train line to the section 13, until the pressure within the line reaches a certain degree, necessary to actuate or open the valve 27. This valve can be adjusted or regulated to open under any desired pressure, and when it assumes an opened position, the air pressure flows through the passage 24 into the passage 25, acting upon the bottom of the piston 18 to elevate the valve in its entirety to the position indicated by dotted lines in Figure 2. This constitutes the closed position of the valve which it maintains under pressure against the tension of the spring 23. Say for instance, that the normal pressure of the air line to the valve casing 10 is seventy pounds, and that the valve 27 was adjusted to open under a pressure of sixty pounds. When the pressure within the casing 10 is sufficient to open the valve 27, allowing the valve proper to assume its closed position, the said valve closes communication between the nipples 11 in so far as any direct communication is concerned through the casing 10. The air pressure then admitted to the casing at the right hand side thereof passes through the arcuate-shaped passage 32 into the reducing valve A, and thence into the passage 33 to the nipple at the left hand side of the valve casing 10. The reducing valve under these conditions would be adjusted to maintain a maximum pressure of sixty pounds of air in the train line system at the left hand side of the valve casing, as compared to the normal pressure of seventy pounds on the right hand side

of the valve casing as above stated. The engineer applies the brakes, in the usual manner and as the seventy pound pressure at the right hand side of the valve must be reduced first, before any reduction in the air line pressure can take place in the air line, leading from the opposite side of the valve, the brakes at the front end of the train are applied in advance and independently of the brakes at the rear of the train. When the train line is charged to effect a release of the brakes, the latter at the rear of the train are released prior to the release of the brakes at the front of the train. Incident to the application of the brakes, the spring 23 functions to move the valve to its opened position and thus establish direct communication between the nipples 11 through the valve casing, and with the return of this valve to the position illustrated in Figure 2, the air beneath the valve is forced out of the casing 10 through the port 31. By reason of the construction and contemplated operation of the valve thus far described, it is manifest that the brakes at the front of the train are not only initially applied as compared with the brakes at the rear of the train, but the application of the brakes at the front is so effective that it properly takes care of the slack which occurs in a long train, incident to the application of the brakes, so that the brakes throughout the entire train may be applied without the draw bars being subjected to undue strain, which frequently results in separating the draw bars from their connections.

In Figure 4, I have illustrated a somewhat modified construction which is primarily intended for use to alternately apply and release the brakes at the opposite ends of the train when descending a mountain or a steep grade for the purpose hereinabove clearly set forth. As shown in Figure 2, the valve casing 10 is provided with a nipple 35 which projects from the casing 10 and communicates with the interior thereof, and which nipple has an exhaust port 36. Normally, or in other words, when the valve is used under ordinary conditions as above described, the nipple 35 as well as the exhaust port 36 is closed by a plug 37. However, should the valve in its entirety be used on a train about to pursue a mountainous journey, the valve casing 10 would be reversed to position the nipple 11 adjacent which the valve 27 is arranged to the engine side of the air line, after the plug 37 has been removed and a relief valve 38, similar in construction to the valve 27, positioned within the nipple 35. Aside from the substitution of the valve 38 for the plug 37, the construction of the valve illustrated in Figure 4 is similar to the construction as shown in Figure 2.

When the structure is used with the valve

38, and the valve reversed in the manner above described, the air pressure admitted to the casing 10 at the engine side of the valve, actuates the valve 27 in the manner 5 hereinabove described to elevate the valve 20 to its closed position as shown by dotted lines in Figure 2. In this use of the valve, the reducing valve A illustrated in Figure 1 is dispensed with, and the openings 34 in 10 the adjacent ends of the arcuate-shaped passages 32 and 33 are plugged or otherwise suitably closed. Subsequent to the closing of the valve 20 as indicated by dotted lines in Figure 2, a certain portion of the air 15 pressure in the air line at the left hand side of the valve is allowed to escape through the port 36 of the nipple 35, the amount of pressure allowing to escape depending upon the adjustment of the valve 38, which can be 20 regulated accordingly.

For instance, if the normal air line pressure is seventy pounds, the valve 27 is adjusted so that it will not open unless subjected to overcharge or pressure, or in other 25 words, a pressure above seventy pounds. The running position of the valve is illustrated in Figure 2, so that the pressure throughout the entire air line would be approximately seventy pounds. Now, when it 30 is desired to apply the brakes, the air line is overcharged sufficiently to open the valve 27 which admits air into the casing 10 beneath the piston 18, lifting the valve against the tension of the spring 23 until the valve 35 assumes its closed position. Direct communication is then cut off between the nipples 11, and the pressure in the air line at the left hand side of the valve, subsequent to closing the latter is allowed to escape 40 through the by-pass 39 and the valve, and subsequently find its way to the atmosphere through the port 36. It is of course understood that the valve 38 is regulated to permit of this decrease in pressure in the air 45 line at the left hand side of the valve, and it is incident to this decrease in pressure that

the brakes of the rear of the train are applied. When the overcharge is reduced at the engine side of the valve in order to apply the brakes at the front of the train, the 50 spring 23 returns the valve to its normal position illustrated in Figure 2, at which time the air line at the left hand side of the valve is charged.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:

1. In an air brake system, a valve arranged in the air line, means for providing 65 a variance in pressure in said line at the opposite sides of the valve, and said valve being operable to control the alternate application of the brakes at opposite ends of the train.

2. In an air brake system, a valve including a casing arranged between and communicating with adjacent air line sections, means providing for a variance of pressure in said sections, and a pressure actuated 75 valve operating within the casing to control said communication, whereby the brakes are alternately applied at the opposite ends of the train.

3. In an air brake system, a valve including a casing arranged between and communicating with the adjacent air line sections, means for providing a variance of pressure in said sections, and a spring pressed valve slidably within the casing and 85 actuated by the fluid to control said communication between the section, whereby the brakes are alternately applied at opposite ends of the train.

In testimony whereof I affix my signature.

OSCAR G. PENDLETON.
